[57] CLAIM

The ornamental design for an antenna module for PCMCIA UHF wireless modems, as shown and described.

DESCRIPTION

FIG. 1 is a front, top and right isometric view of an antenna module for PCMCIA UHF wireless modems showing our new design;

FIG. 2 is a rear elevational view thereof;

FIG. 3 is a left side elevational view thereof; and,

FIG. 4 is a bottom plan view thereof.

The broken lines in all views are for illustrative purposes only and form no part of the claimed design.
